UNITED STATES PATENT OFFICE.

ARTHUR S. TREW, OF PORTLAND, OREGON.

CARD-ASSORTING MACHINE.

1,214,394.

Specification of Letters Patent. Patented Jan. 30, 1917.

Application filed April 20, 1912. Serial No. 692,146.

To all whom it may concern:

Be it known that I, ARTHUR S. TREW, a citizen of the United States, residing in the city of Portland, county of Multnomah, and State of Oregon, have invented certain new and useful Improvements in Card-Assorting Machines, of which the following is a specification.

My invention relates to card assorting machines, and more particularly to a machine by means of which cards, tickets, and the like, can be rapidly assorted and distributed into different apartments or pockets.

Among the salient objects of the invention are: to provide a machine of the character referred to comprising in combination a container to receive and hold the cards, an ejector for discharging the cards therefrom, a series of apartments or pockets for receiving the cards in classified order, and a distributor interposed between said container and said apartments, with mechanism for operating said ejector and said distributor; to provide in combination with such a device a series of keys with operating connections with said ejector and with said distributor, and by means of which said ejector and said distributor are put into operation; to provide in a machine of the character referred to a series of electro-magnets or solenoids, for operating said ejector and said assorter, with a source of electric energy therefor, and with circuit connections including said magnets, whereby the manipulation of said keys operates to connect said source of electric energy with said electro-magnets, which operate said ejector and said distributor; to provide in such a machine, in combination with the ejector, means for facilitating the discharge of a card from the container, and for throwing it into the distributor; and, in general, to provide a new, practical, and efficient machine by means of which cards, tickets, and the like, can be rapidly assorted and deposited into classified receiving apartments or pockets by simply manipulating a set of keys, which keys correspond, respectively, with the receiving apartments or pockets.

In order that others may clearly understand my invention, I have shown in the accompanying sheets of drawings one practical form or embodiment thereof, which I will now describe.

In the drawings: Figure 1 is a front or face view of a container with an ejector mounted thereupon; Fig. 2 is a cross sectional view thereof taken on line 2—2 of Fig. 1; Fig. 3 is an end sectional view of a distributor taken on line 3—3 of Fig. 4, the relative position of the container being indicated in dotted lines; Fig. 4 is a top plan view of the distributor; Fig. 5 is a side view of said distributor; Fig. 6 is a diagrammatic view illustrating the wiring and electric connections between the keys and the various operating electro-magnets; Fig. 7 is a plan view of a keyboard with binding posts for electric connections; and Fig. 8 is a sectional view through said keyboard.

Referring now to Figs. 1 and 2 of the drawings, the container which I have shown for purposes of illustration, comprises a case or frame, 1 with a sight frame 2 in the front portion thereof, through which the faces of cards 3 can be seen. Mounted upon said frames are cross pieces 4 and 5, upon which are mounted electro-magnets 6—6, with circuit connections to binding posts 7—7. Also mounted upon said cross piece 4, is a rocking frame 8, pivotally mounted and carrying an armature member 9, adapted to be attracted to said electro-magnets 6—6, when they are energized, said rocking frame being provided at its rearward end with a spring 10 for holding it in a normal, inoperative position. Upon the forward end of said rocking frame 8 is an ejector member 11, adapted to be moved downwardly between the sight frame 2, and the outermost card, said ejector member 11 being provided upon its rear face with a shoulder 12, adapted to engage the outermost or front card and move it downwardly through a slot in the bottom of the container and adjacent the sight frame 2. The cards in the container are pushed forwardly therein by a follower 13, provided at its sides with antifriction guide rolls arranged to move in the slots 15—15 in the inner faces of the side members of the container. This follower 13, in the present showing, is drawn forwardly by means of a supported weight 16, connected thereto by means of a cable 17, working over a pulley 18. The cards are thus frictionally held against the sight frame 2, until the front or outermost card is pushed downwardly by the ejector member 11,

when the electro-magnets 6-6 are energized and the armature 9 upon the pivotally mounted ejector frame 8, is attracted thereto.

5 In order to facilitate the ejection or removal of a card from the container I have provided, near the discharge opening or slot in the container bottom, rollers 19 and 20. Roller 19, preferably being the larger, is extended across the front of the container, and 10 is driven, in the present showing, by a small motor 21. The roller 20 is yieldingly mounted in a slide-way 21 and is adapted to be held against roller 19 by a coiled spring 22. 15 Thus it will be seen that as soon as the front or outermost card is pushed through the opening in the bottom of the container by the ejector member 12, it is immediately gripped between the rollers 19 and 20, and 20 thrown downwardly through a guide chute 23, illustrated in Fig. 3. Mounted immediately under said guide chute 23, is what I will call an assorter, and comprises a series 25 of thin sheet metal leaves 24, of rectangular form, pivotally mounted at their lower edges and at their ends, within a rectangular opening 25 in a supporting base, or table, 26. At their lower edges said assorting plates or leaves are spaced apart as indicated in Fig. 30, so that the spaces therebetween register with chutes or guide-ways *a*, *b*, *c*, *d*, *e*, *f*, *g*, *h*, *i*, *j*, *k*, and *l*.

I will now describe one means for operating said assorter, and for moving the leaves 35 24 whereby to open into register with the discharge chute 23, the different passage-ways leading to the chutes *a*, *b*, *c*, *d*, *e*, *f*, *g*, *h*, *i*, *j*, *k*, and *l*.

a', *b'*, *c'*, *d'*, *e'*, *g'*, *h'*, *i'*, *j'*, *k'*, and *l'*, 40 designate a series of electro-magnets or solenoids, the armatures of which are connected through levers to the ends of said assorting leaves or sheets 24, in a manner which I will now describe. When these electro-magnets are demagnetized, said leaves rest normally in the positions shown in Figs. 3 and 4; that is, six of them lie to the right, and five of them lie to the left, leaving a middle opening in direct alignment between 45 the discharge chutes 23, and the chute *f*, below, which leads to one of the receiving pockets, or apartments, not here shown. For this reason there is no electro-magnet corresponding with said chute *f*.

55 Mounted adjacent each set of electro-magnets, or solenoids, is a pair of long arches, as 27-27, carrying adjustment screws 28-28, at each magnet, between which screws the armatures of the respective magnets move. By this means the movement of the armatures may be regulated for the purpose of controlling the movement of the various assorting leaves 24. The armatures are designated, respectively, *a*², *b*², *c*², *d*², *e*², 60 *g*², *h*², *i*², *j*², *k*², and *l*². They stand in a ver-

tical position and are pivotally mounted to turn upon a common axis, represented as a supporting rod 29, Fig. 5. The lower ends of said armatures are arranged to be attracted by the magnets and to be drawn thereto, while the opposite ends thereof are extended upwardly for attachment, through suitable levers and yokes, to the different assorting leaves 24.

70 In the present arrangement the armatures of the solenoids on one side, as *a*², *b*², *c*², *d*², and *e*², Figs. 3 and 4, are connected to the assorting leaves on the opposite side, while the armatures of the solenoids on said opposite side, as *g*², *h*², *i*², *j*², *k*², and *l*², are 75 connected to the assorting leaves on the same side as are the first solenoids. The assorting leaves are each provided with yokes which are connected at their ends to the ends of the leaves, and at or near their middles. 80 said yokes are connected with operating levers connected with the armatures of the several solenoids. These several yokes are designated, respectively, *a*³, *b*³, *c*³, *d*³, *e*³, *g*³, *h*³, *i*³, *j*³, *k*³, and *l*³, and are connected with 85 their respective armatures through levers, designated, respectively, *a*⁴, *b*⁴, *d*⁴, *e*⁴, *g*⁴, *h*⁴, *k*⁴, and *l*⁴. Armature *c*² is connected direct to yoke *c*³, as are also armatures *i*³, and *j*³. Levers *a*⁴ and *b*⁴ are pivotally supported 90 upon a rack 30, while levers *d*⁴ and *e*⁴ are pivotally supported upon a rack 31, Fig. 5. Levers *g*⁴ and *h*⁴ are pivotally supported 95 upon a rack 32, and levers *k*⁴ and *l*⁴ are pivotally supported upon a rack 33. Said armatures are drawn away from the magnets when the latter are demagnetized by means of coiled springs, as 34-35.

100 Referring now to Fig. 7, I have shown a keyboard for controlling the admission of current to the several electro-magnets, or solenoids, there being a key for each magnet of the assorter, and one for the magnet on the container, for operating the ejector. Said keys are designated, respectively, A, 110 B, C, D, E, F, G, H, I, J, K, and L, said keys being adapted to be connected in the circuits to the various electro-magnets, through suitable binding posts, as indicated, so that the pressing of a key operates to 115 complete a circuit which includes certain of the electro-magnets of the assorter, and also the magnet for operating the ejector. Key F completes a circuit which includes only the magnet which operates the ejector, 120 while the assorting leaves are left undisturbed, in their normal positions with the middle passage-way, as shown in Fig. 3, open in register with the chute *f*.

125 The operation of the embodiment of the invention which I have just described may be briefly stated as follows: There are 12 of the chutes *a* to *l*, leading to as many different receiving pockets or apartments, and there are 12 keys corresponding therewith. 130

The operator, by a glance at the face of the front card in the container, shown in Fig. 1, knows into which pocket or apartment it should go. If, for example, it goes through 5 chute *a*, he presses the *A* key, which completes a circuit through the electro-magnets *a' b' c' d'* and the ejector magnets *6—6*. This operates to simultaneously draw down the ejector, which pushes said card out of 10 the container and into a position to be gripped by the rollers *19—20*. The electro-magnets *a' b' c' d'*, having been energized, have moved the assorting leaves to a position to open a passage-way from the guide 15 chute *23*, beneath the rollers *19—20*, to chute *a*, through which the card is thrown to the desired pocket or apartment, in register therewith. If the card belongs in the pocket fed by chute *f*, the *F* key is pressed 20 and only the magnet on the container for operating the ejector is included in the circuit. The ejector is drawn down and the card is thrown through the middle passage-way, which is normally open when all of the 25 electro-magnets of the assorter are demagnetized, and the assorting leaves are at rest in the positions shown in Fig. 3, so that the card passes through the assorter to chute *f*, and into the proper pocket or apartment in 30 register therewith.

Broadly considered, my invention contemplates a container for receiving and holding cards, or tickets, an ejector for pushing the cards out, one by one, an assorter for directing the cards to the proper pockets or apartments, with a keyboard, the keys of which correspond in number to the respective receiving pockets, or apartments and have operative connections, whereby to 35 simultaneously operate the ejector, and the assorter for passing the card from the container to its proper pocket or apartment. I prefer to use electro-magnets, with a source 40 of electric energy, in combination with keys, for accomplishing this function.

Referring now to Fig. 6, I have shown a diagrammatic view of a series of electro-magnets, and connections for operating an assorter, including a magnet for operating 45 an ejector, and also including electric batteries, and keys for making and breaking the various circuits which control the different electro-magnets. I have designated these keys to correspond with the keys 50 shown in Fig. 7, namely, *A*, *B*, *C*, *D*, *E*, *F*, *G*, *H*, *I*, *J*, *K*, and *L*. I have also designated the magnets to correspond with the electro-magnets shown in Figs. 3, 4 and 5, namely, *a' b' c' d' e' g' h' i' j' k' l'*, and have designated the magnet which operates 55 the ejector as *6—6*, to correspond with the ejector magnet upon the container, shown in Fig. 2. I am aware that various connections can be made from a series of electro-magnets for operating an assorter, and also

that various forms of assorters can be interposed between the container and the receiving pockets, and I do not, therefore, limit my invention to the particular form of assorter here shown for purposes of illustration, or to the lever connections used therefor. By pressing the key *A*, a circuit is completed through the electro-magnets *a' b' c' d'* and *e'*, the ejector magnets *6—6*, and the batteries *6'* and *A'*. The electro-magnets *a' b' c' d' e'* operate the assorter, and bring into register with the discharge opening from the container, the proper chute or passage-way leading to the proper pocket or apartment, while the electro-magnet *6*, operates the ejector, and starts the card from the container. If the key *F* is pressed, only electro-magnets *6—6* are energized, through the battery *6'*, and a card is started from the container through the middle chute or 85 passage-way, which normally opens in register with the discharge opening from said container. By pressing any of the other keys in the diagram, it will be understood, and it can be readily traced upon the drawing, that the different circuits are completed to magnetize and bring into operation the electro-magnets necessary to operate the assorter, and bring into register with the discharge opening from the container the desired passage-way or chute leading to the proper pocket or apartment. It will thus be seen that by pressing any one of the keys, electro-magnets are energized which operate to simultaneously eject 90 a card from the container, and to move the distributor to put into register a passage-way therethrough to the desired pocket or apartment.

I do not, therefore, limit the invention to 105 the embodiment shown for purposes of illustration, except as I may be limited by the hereto appended claims, broadly interpreted.

As to the broader aspects of my invention 110 herein disclosed, the same will be claimed in my co-pending application Serial No. 6159, filed Feb. 4, 1915, covering applicant's more perfected type of machine, and which application, so far as common subject-matter 115 is concerned may properly be considered a continuation of this case. The claims herein retained will be directed to those features of the machine distinguishing the same from said later machine.

I claim;

1. In a machine of the character described, a card container adapted to hold a series of cards in edge-wise position and having an open side, a magnetically operated ejector mounted to be reciprocated vertically in said container for ejecting the cards therefrom one by one.

2. In a machine of the character described, a card container adapted to hold a

- series of cards in edge-wise position and having an open side, a magnetically operated ejector mounted to be reciprocated vertically in said container for ejecting the 5 cards therefrom one by one, and means for manually controlling said magnetically operated ejector at will.
3. A card ejecting unit for distributing machines comprising a container for the 10 cards to be distributed, and means for ejecting the individual cards from the container comprising a card engaging element, and a magnetic actuator for said element mounted on the card container.
- 15 4. A card ejecting unit for distributing machines comprising a container for the cards to be distributed, and means for ejecting the individual cards in a downward direction from the container comprising a 20 card engaging element, and a magnetic actuator for said element mounted upon the top of the card container.
- 25 5. A card ejecting unit for distributing machines comprising a container for the cards to be distributed, and means for ejecting the individual cards from the container comprising a card engaging element, an armature associated with said element pivotally mounted on the container, and a magnet also mounted on the container in position to operate the armature.
- 30 6. A card ejecting unit for distributing machines comprising a container for the cards to be distributed, and means for ejecting the individual cards from the container comprising a card engaging element, an armature pivoted on the container associated 35 at one end with said element, a spring between the opposite end of the armature and the container for moving the armature in

one direction, and a magnet also mounted on the container for attracting the armature in the opposite direction.

7. In a machine of the character described, a card container adapted to hold a 45 series of cards in edge-wise position, a magnetically operated ejector mounted to discharge a card in a vertical direction, and means for manually controlling said magnetically operated ejector at will, in combination with a plurality of distributing pockets below the container, and switches to deflect the cards to their appropriate containers, said switches being connected to be also actuated by said manually controlled means. 50

8. In a machine of the character described, a card container adapted to hold a series of cards, means for ejecting the cards individually to discharge the same in a vertical direction, a plurality of distributing 60 pockets, switches below the container adapted to deflect the cards to their appropriate containers, and a series of key actuators each adapted by a movement in one direction to throw the appropriate switch and operate 65 the ejector to discharge a card.

9. In a machine of the character described, a card container adapted to hold a 70 series of cards, means for ejecting the cards individually to discharge the same in a vertical direction, a plurality of distributing pockets, switches below the container adapted to deflect the cards to their appropriate containers, and a series of key actuators each adapted to effect simultaneous ejection of a 75 card and setting of an appropriate switch.

ARTHUR S. TREW.
